TEAR-STRIP TYPE CONTAINER AND
RECLOSURE THEREFOR

Ivan D. Thornburgh, Leonia, N. J., assignor to
American Can Company, New York, N. Y., a
corporation of New Jersey

Application December 11, 1944, Serial No. 567,662

2 Claims. (Cl. 220—54)

1

The present invention relates to a metal air-tight tearing strip container or can having an interior collar member secured within the body wall in an air-tight hermetic joint and has particular reference to a container of this type which can be reclosed by the released cover formed for snapping engagement with the collar in an air-tight or hermetic seal after the container is opened by removal of the tearing strip.

The usual hermetically sealed tearing strip container when once opened by removal of the tearing strip can only be re-covered, as contradistinguished from resealed, by the detached can end or cover. As a result of this condition there are no restrictions, or at least very few restrictions against free circulation of air in and through the product remaining in the can. When the can is opened air comes in contact with the product and this air is present and cannot ordinarily be removed. For many products the loosely fitting cover of the can is adequate especially when the remaining product is quickly consumed. Some products such for example as coffee, dried milk and other powdered dairy products will keep much better if additional air is prevented from circulating into and through that portion of the product which has not been used and which remains in the opened can. In other words, an air-tight reclosure for cans of this general type is desirable and the present invention contemplates an improved can construction which provides for a simple and efficient air-tight reclosure without impairing in any way the efficiency of an easily opened hermetically sealed can.

An object of the present invention is the provision of an improved construction for a tearing strip container having an interior collar wherein in addition to the usual air-tight sealing of the can when it is initially closed on its contained product there is also provided an air-tight reclosure.

Another object of the invention is the provision of a tearing strip container having an interior collar which is so formed as to adapt that part of the can for air-tight resealing by the cover which has been removed in opening the can.

Yet another object is the provision of such a reclosure collar container having a cover which is provided with dual sealing regions so that in addition to the usual hermetic sealing of the can

and cover there is also provided a proper cooperation between the removed cover and the collar of the opened can, thus embodying the additional feature of an air-tight reclosure.

Still another object is the provision of an easily opened tearing strip collar container wherein the removed double gasket lined cover has a positive snap-on continuous engagement with the collar, thereby insuring a continued air-tight sealing reclosure without impairing the ease of reopening of the can.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a tearing strip container embodying the present invention;

20 Fig. 2 is an enlarged sectional detail of the closed container as viewed along the section line 2—2 in Fig. 1; and

Fig. 3 is a view similar to Fig. 2 but showing the 25 opened container with its detached cover in air-tight seal reclosing position.

The present invention contemplates a container having a body 11 and end closures 12 secured to the body in double seams 13. The novelty of the container of the present invention is associated 30 with its upper or top end while any suitable bottom end may be used. Accordingly the upper end is shown in some detail in the accompanying drawing.

35 Adjacent the top and just below the upper end seam 13 the body wall 11 is cut through with a pair of parallel score lines. These include a lower score line 15 and an upper score line 16 setting off a tearing strip 17. At the side seam of the container, the tearing strip terminates in an extended tongue 18 which provides for engagement of the opening key. The body wall above the score line 16 merges into the double seam and a sealing gasket or lining compound 19 located in the usual sealing gasket channel is interposed between the body and cover parts in a conventional manner.

40 A collar 21 is located in the can body 11 being positioned adjacent the top end of the body. This collar preferably is secured to the body in an air-tight joint. To properly locate the collar both 45 the collar and the body walls are preferably

beaded together, an outwardly extending collar bead 22 being seated within a corresponding body bead 23. A suitable sealing compound can be used between the beads to obtain the desired air-tight joint or the lower edge of the collar all of the way around may be soldered to the body wall as at 24.

The collar 21 extends up in close engagement with the body wall to a position just above the lower score line 15 when the collar wall bends inwardly at a rounded annular edge 25, into a conical wall 26 which extends at about 30° from the horizontal. The upper portion of the conical wall terminates in an outward, open reclosure curl 27. This construction of collar provides a smooth mouth for the container when opened and also assists in the desired reclosure as will be evident as the description proceeds.

The top end closure or cover 12 when in seamed position extends downwardly inside the body and inside the double seam 13 to a point below the upper score line 16 where it bends inwardly in a curved annulus 31. At this annulus the cover wall then extends inwardly and downwardly in an inverted conical wall 32. The bottom of the conical wall 32 is positioned just below the center of the collar curl 27 and is thence doubled back on itself in a sharp bend 33. The wall 32 thereupon merges into a reclosure shelf section 34 which lies closely against and on top of the conical wall. Above, the shelf section 34 merges into an annular arched bead 35 which provides an annular groove 36 on the underside of the cover. This constitutes an inwardly spaced reclosure gasket channel. A sealing gasket or compound lining 37 preferably is contained within the groove 36. It will be thus apparent that the gasket 19 of the double seam and the gasket 37 of the groove 36 constitute dual gasket sealing regions of the can cover.

At the inside, the arched bead 35 of the cover merges into a central cover panel 38. The groove 36 is so positioned inwardly of the double seam of the cover as to be directly above the collar reclosure curl 27 when the cover is in place on the body. When the cover 12 is first seamed onto the body 11 in the form as shown, the reclosure curl is embedded in the gasket 37 of the cover groove 36 but this is merely a preferred form. Obviously it is not necessary to have a seal at this place in the can until it is to be reclosed after opening. In such a construction, however, the container is doubly sealed, there being air-tight joints at both gasket sections 19 and 37.

When the container is opened by removal of the tearing strip 17 which may be done in the usual manner as by application of a key to the extended tongue 18, the cover 12 together with the top portion of the body wall 11 between the double seam and the top score line may be lifted from the container. In the event that only a portion of the product is consumed the container may be reclosed merely by application of the removed cover unit. In applying the cover a slight rotation as the cover is pressed down, fully engages the annular bent edge 33 around the engaged periphery of the open reclosure collar curl 27 causing a slight yielding action of the curl as the cover fully locks under the collar. When so engaged the cover, according to the variation shown, is returned to the same position it occupied on the can body prior to opening. In this position the reclosure curl 27 is again embedded in the gasket 37 of the cover and an air-tight seal is thus effected between the opened can body and the applied reclosure cover.

This seal for reclosing of the container prevents circulation of air into and through the product and only the air which has been trapped in the can when it is reclosed again is present in contact with the product. For many products which would deteriorate by oxidation where a large quantity of air freely circulates through the product, the presence of a small amount of dead air confined in the head space of the can above the product is negligible. It is for such products that the present can construction is useful and has been perfected.

Such a can may be reopened and reclosed a number of times, it only being necessary in removing the reclosure cover to pull the annular edge 33 from its engagement with the open reclosure curl 27, the latter yielding sufficiently to permit easy engagement or disengagement of the parts.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

- 30 1. In an air-tight sheet metal container capable of air-tight reclosure, a container body having score lines defining a removable tearing strip for opening the container, a collar located inside of said body and hermetically sealed therein and at the top extending inwardly at an angle to form a conical wall back of said tearing strip, said wall terminating in an outer reclosure curl, a cover having a primary sealing gasket channel and an inwardly spaced reclosure gasket channel
- 35 double seamed to said container body and extending downwardly and inwardly below the double seam as an inverted conical wall, the lower end of the inverted wall being doubled back on itself to provide a reinforced reclosure shelf section surrounding said reclosure gasket channel, and sealing gaskets in the cover channels, the gasket in said primary sealing channel being enclosed in said double seam and providing an air-tight permanent joint between the body and cover and the gasket in said reclosure channel providing an air-tight joint between the cover and said reclosure curl for reclosing the container after it has been opened by removal of said tearing strip, the shelf section in said cover engaging under and yieldably surrounding said reclosure curl to embed the latter in said reclosure gasket in an air-tight reclosure joint when the released cover is applied to the opened container.
- 40 2. In an air-tight sheet metal container capable of air-tight reclosure, a container body having score lines defining a removable tearing strip for opening the container, a collar located inside of said body and hermetically secured thereto, said collar extending inwardly at an angle to form an inwardly and upwardly extending conical wall spaced inwardly from said tearing strip, said wall terminating in a reclosure curl spaced inwardly from said body wall, a cover having dual gasket sealing regions consisting of a primary sealing gasket channel and a reclosure sealing gasket channel spaced inwardly substantially the same distance from said outer body wall as said reclosure curl, said cover being secured to said container body and extending downwardly and inwardly at an angle to form a conical wall, said
- 45
